Primary Examiner — Catherine Tuttle(74) *Attorney, Agent, or Firm* — Holland & Hart LLP(57) **CLAIM**

The ornamental design for a cubic logic toy, as shown and described.

DESCRIPTION

The file of this patent contains at least one drawing executed in color. Copies of this patent with color drawings will be provided by the Office upon request and payment of the necessary fee.

FIG. 1 is a top front perspective view of a cubic logic toy, showing my new design;

FIG. 2 is a bottom rear perspective view of FIG. 1;

FIG. 3 is a top view of FIG. 1;

FIG. 4 is a bottom view of FIG. 1;

FIG. 5 is a left side view of FIG. 1;

FIG. 6 is a right side view of FIG. 1;

FIG. 7 is a front view of FIG. 1; and,

FIG. 8 is a rear view of FIG. 1.
